FLEXIBLE CANTEEN

Roy E. Allenbach, Pueblo, Colo.

Application November 4, 1957, Serial No. 48,340

Term of patent 14 years

(Cl. D58—8)

Fig. 1 is a front face view of a flexible canteen showing my new design; and

Fig. 2 is a side edge view thereof.

The rear face of the flexible canteen is plain and unadorned. The side opposite to Fig. 2 is similar to that shown in Fig. 2, except in reverse.

The broken lines shown on the drawing are representative of stitching.

The drawing is shaded to indicate contrast in colored areas, and the shading shown partially applied to said areas is intended to completely cover the surfaces of the canteen as disclosed.

I claim:

The ornamental design for a flexible canteen, as shown, and described.
